UNITED STATES PATENT OFFICE

107,575

DESIGN FOR A GLASS BOTTLE

Lawrence J. Kihm, Pittsburgh, Pa., assignor to J. T. & A. Hamilton Company, a corporation of Pennsylvania

Application September 17, 1937, Serial No. 71,657

Term of patent 3½ years

To whom it may concern:

Be it known that I, Lawrence J. Kihm, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

In the drawing:

Fig. I is a front elevation of a glass bottle showing my new design; Fig. II is a view of the bottle in side elevation; and Fig. III is a view in cross-section, taken on the plane III, III of Fig. I.

I claim:

The ornamental design for a glass bottle substantially as shown.

LAWRENCE J. KIHN.
